PALETTE

Clifford T. Lloyd, Aurora, Colo., assignor to Lloyd Products, Inc., a corporation of Colorado

Filed Feb. 13, 1967, Ser. No. 5,792

Term of patent 14 years

(Cl. D44—15)

Fig. 1

Fig. 2

Fig. 4

Fig. 3

FIG. 1 is a perspective view of a palette showing my new design.

FIG. 2 is a perspective view similar to FIG. 1 showing a section taken along line 2-2 of FIG. 1.

FIG. 3 is a reduced side elevational view thereof.

FIG. 4 is a reduced top plan view thereof.

I claim:

The ornamental design for a palette, as shown.
